UNITED STATES PATENT OFFICE.

JOHN F. MILLER, OF LEE, ASSIGNOR OF ONE-HALF TO JAMES L. CARR, OF WHITE COUNTY, INDIANA.

MUSIC-HOLDER.

SPECIFICATION forming part of Letters Patent No. 423,789, dated March 18, 1890.

Application filed October 17, 1888. Serial No. 288,337. (No model.)

To all whom it may concern:

Be it known that I, JOHN F. MILLER, a citizen of the United States, residing at Lee, in the county of White and State of Indiana, have invented certain new and useful Improvements in Music-Holders; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to book-holders, and is especially designed for holding music-books open on a music stand or rest.

The improvement consists of two levers pivoted to a base and a spring interposed between the levers to force their arms against the book with sufficient pressure to hold it open. By preference the base is provided with a case that incloses the spring, and the ends of the spring extend and engage with the levers or with arms projecting from the levers. The levers are approximately V-shaped and have circular enlargements at the junction of their branches, which overlap one another and form a covering for the case that incloses the spring.

The improvement further consists of the peculiar construction and combination of the parts, which will be hereinafter more fully described and claimed, and shown in the accompanying drawings, in which—

Figure 1 is a top plan view of the holder, showing its application; Fig. 2, a rear end view, parts being broken away, of the holder; Fig. 3, a perspective view of the base or support for the levers, showing the spring in position; Fig. 4, a section on the line $x-x$ of Fig. 1, and Fig. 5 a perspective view of the levers.

The levers A and A', similarly constructed, are approximately V-shaped, having the branches a and a' at about right angles to one another, and having the circular enlargements a^2 at the point of convergence of the two branches, which overlap and are pivoted together and to the base or support C by the

pivot D. The inner branches a' of the levers are sufficiently long to rest on the leaves of the book near their edges, and their ends are flat and curved, as shown, to give a neat finish and obtain a broad surface to rest against the book without marring the latter. The branches a project outward and form handles to be grasped by the hand to bring them close together, being provided with knobs on their outer ends to hold the branches out while not in use by pressing the knobs past each other and move the branches or arms a' from the book or outward to permit the book to be inserted between the rest and the said arms.

The base or support C has its outer end slightly inclined to throw the arms a' upward, and is provided with a circular rim F, which forms a case for the spring G. The arms g of the spring project through an opening in the side of the case and bear on the pins f, extending from the handles of the levers to force the said handles apart and the arms a' against the leaves of the book. The inner end of the base or support has openings for the insertion of screws or other fastening means for securing it in place on a book-rest or the music-rest of a piano-forte.

Having thus described my invention, what I claim, and desire to secure by Letters Patent, is—

1. A music-holder composed of a base or support, two levers pivoted together and to the base, and a flat or coil spring for forcing the outer ends of the levers outward, whereby they will press on the book, substantially as shown and described.

2. In a music-holder, the combination of the base, the two approximately -V-shaped levers pivoted together and to the base, and the spring for forcing the outer ends of the levers outward to press on the book, substantially as described and set forth.

3. The combination of the base having a rim to form a case, the spring arranged in the case and having its ends extended beyond the case to engage with and force the outer ends of the levers outward against the book, and the two levers pivoted together and to the case and forming a cover for the said

case, substantially as and for the purposes described.

4. The combination of the base, the two approximately-V-shaped levers having circular enlargements at the point of divergence of their branches, the pivot uniting the levers and the base, and the spring for forcing the outer ends of the levers outward to press on

the book, substantially as and for the purposes described.

In testimony whereof I affix my signature in presence of two witnesses.

JOHN F. MILLER.
